(57) **CLAIM**

The ornamental design for an electric bicycle as shown and described.

DESCRIPTION

FIG. 1 is a front-left side perspective view of an electric bicycle embodying my new design;

FIG. 2 is a rear-right side perspective view thereof;

FIG. 3 is a front-right side perspective view thereof;

FIG. 4 is a rear-left side perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.

The broken lines depict portions of the electric bicycle that form no part of the claimed design.

1 Claim, 10 Drawing Sheets
